UNITED STATES PATENT OFFICE.

THOMAS M. NORTH, OF BROOKLYN, NEW YORK, ASSIGNOR, BY DIRECT AND MESNE ASSIGNMENTS, TO ROBT. HOE AND CHARLES W. CARPENTER, OF NEW YORK, N. Y., UNDER THE FIRM-NAME OF R. HOE & COMPANY.

PRINTING-PRESS.

SPECIFICATION forming part of Letters Patent No. 703,665, dated July 1, 1902.

Application filed December 22, 1897. Serial No. 663,003. (No model.)

To all whom it may concern:

Be it known that I, THOMAS M. NORTH, a subject of the Queen of Great Britain, residing at Brooklyn, county of Kings, and State 5 of New York, have invented certain new and useful Improvements in Printing - Presses, fully described and represented in the following specification and the accompanying drawings, forming a part of the same.

10 This invention relates to mechanism for presenting offset-sheets to and removing them from the impression-cylinder. In constructions heretofore suggested it has been proposed to mount the offset in the form of a 15 web upon a supply-roll within the impression-cylinder and to cause it to move at intervals from a supply-roll to a take-up roll also mounted within the cylinder. This arrangement has the disadvantage of necessary complexity 20 of mechanism in order to provide for the movement of the tympan-web, and it has the further disadvantage that inasmuch as the offset or tympan web is shifted after each impression successive impressions do not register with each other, and consequently the 25 life of the offset-web is reduced substantially beyond that which it would have if it remained in a fixed position relatively to the impression-plate until its capacity was exhausted. It has also been proposed to feed 30 separate sheets to the impression-cylinder by hand; but this operation is of course inconvenient and expensive in that it requires the attention more or less constantly of the operator.

35 In carrying out the present invention it is proposed to supply the tympan or offset sheet from a supply-roll placed upon the frame of the machine outside of the cylinder and to cause it to be automatically fed to the impression-cylinder and the tympan or offset sheets to be automatically detached from the web at intervals when required to remain upon the impression-cylinder during a number 45 of impressions and at like intervals when soiled to be automatically released and delivered from the impression-cylinder.

In the practical embodiment of this invention any means desired may be employed for

severing the tympan or offset sheet from the 50 web, and I do not, of course, confine myself to the particular means herein shown, which consists in the use of a perforated web and means for clamping the web so that the sheet may be torn therefrom. Thus an unperforated 55 tympan or offset web may be used and the sheets severed when required by the impression-cylinder by a cutting mechanism.

The invention consists in certain features 60 of construction, which will be hereinafter described in the specification and pointed out in the claims.

In the drawings annexed, forming a part of this specification, Figure 1 is a side view of a press to which my invention has been applied, showing the second impression-cylinder and part of the first impression-cylinder and part of the delivery-cylinder. Fig. 2 is an end view of the same, the line of sight being that shown by the arrow in Fig. 1 and 65 the first impression-cylinder being removed. Fig. 3 shows the position of the grippers when about to seize the end of the tympan-web. Fig. 4 shows the position of the parts at the moment of the severing of the web, the end 70 of the web from which the sheet has just been severed being shown clamped to the feed-table. Fig. 5 represents the position of the grippers when the grippers of the delivery-cylinders are about taking off a printed sheet 75 from the impression-cylinder. Fig. 6 shows the position of the grippers when the grippers of the delivery-cylinders are about taking off a printed sheet, together with the tympan-sheet, from the impression-cylinder; and 80 Fig. 7 is a plan view of a controlling-lever.

The tympan or offset web A, which in the form of machine shown is preferably divided into sheets of proper length by perforations, is mounted in brackets attached to the frame 85 of the machine and between guide-rollers a a', from which it descends over a feed board or table B, having a hinged flap b. The cylinder is provided with the usual grippers C for the printed sheet, mounted upon a shaft 90 C' and actuated by cams (not shown) in the usual manner. For the tympan or offset sheets there is provided a second set of grip-

pers D, fastened upon a shaft D'. From the hub of these grippers are two projecting lugs between which lies a pin attached to a lever d, journaled upon shaft D', alongside of each 5 gripper D. These levers are rotated by the grippers D through their lugs and the pin on the levers, and they carry at their ends, by projecting through holes in the same, pins d', playing through perforations in the edge of 10 the cylinder-shell for the purpose of lifting the edge of the tympan-sheet into reach of the grippers of the delivery-cylinder at the propertime. The blanket-grippers are shown at F. The sheet-grippers abut against the 15 outer surface of the cylinder and the tympan and blanket grippers against different portions of the edge of the cylinder-shell, as shown in Fig. 6.

The shaft D' carries at one end a double- 20 ended lever f, one end of which is pressed by a spring G to close the tympan-grippers and the other end of which carries a roller f', which engages with a cam H to open the tympan-grippers. This cam H slides lengthwise 25 of the cylinder upon two studs h h and is only moved into the path of the roller f' at those intervals in the operation of the press at which it is desired to replace the tympan-sheet. The cam is controlled by a rod h' be- 30 tween two collars, on the outer end of which is the end of one arm of a bell-crank lever h'', to the other arm of which is attached a connecting-rod h''', joined below to a pivoted lever moved in one direction by the spring i 35 and in the other by the cam J during a portion of each revolution of the cam-shaft I. The movement occasioned by the cam J moves the cam H outward, and the spring i tends to move it inward, (into the path of roller f';) 40 but its action is prevented, except at stated times, by the lever K, Figs. 1 and 7, which in its normal position (shown in broken lines in Fig. 7) stands with its end just above the collar l on the connecting-rod h''', preventing it 45 from rising. The lever K is periodically withdrawn by a mechanism which includes a pin k, revolving with the cylinder and which at each revolution moves the wheel k' one tooth. A pin k'' in the same way moves a 50 wheel k'' one tooth for each revolution of wheel k'. As each of the wheels k' and k'' have twenty teeth, the wheel k''' will have but one revolution to four hundred of the cylinder. The wheel k''' carries a cam s, which engages 55 with a roller on lever K. It is obvious that this cam will press back the lever K against its spring K¹⁰ every four hundred revolutions of the cylinder, thereby relieving connecting-rod h'''. The effect of this is to cause the 60 cam H to move temporarily into the path of the roller f', opening the tympan-grippers and permitting the tympan-sheet to be caught by the grippers p of the delivery-cylinder P. Ordinarily the grippers p seize only the printed sheets, as shown in Fig. 5; but when the 65 tympan-grippers are opened they rock the le-

vers d, which in turn force the pins d' outward, lifting the edge of the tympan-sheet into the grasp of the grippers p, as shown in Fig. 6.

In front of the feed-table B is a rock-shaft M, carrying a clamping-bar m and levers m', each of which has a pin riding in a slot of a bracket m'', attached to the table-flap b. The shaft M also carries the sheet-metal paper-guides n. The rock-shaft M is provided with arms n', jointed to a connecting-rod n'', passing down to bell-crank lever O, actuated in one direction by the cam o during a part of its revolution and in the other by the spring R, (which presses downward.) The tendency of the spring R to depress the upper end of lever O is prevented from acting, usually, by the engagement of lever K with a collar r, fixed upon the connecting-rod n''. When, 85 however, lever K is withdrawn, rod n'' de- scends, rocking shaft M from its normal position (shown in Fig. 4) to the position shown in Fig. 3. The levers m', now acting through brackets m'', have pushed down the feed-ta- 90 ble flap b close to the cylinder, and the paper-guides have pressed in the edge of the tympan-sheet to a position where it can be readily grasped by the tympan-grippers. The tym- 95 pan-web is now caught by the tympan-grip- 100 pers and pulled forward by the revolution of the cylinder, (the regular sheet-grippers be- ing open at this point.) When a full tympan- sheet has passed onto the cylinder, the raised portion of cam o causes the shaft M to rock 105 inward until the clamping-bar m descends upon the table-flap b (which at the same time is forced outward by the action of levers m') and clamping the paper prevents further feed. This position is shown in Fig. 4. The con- 110 tinued motion of the cylinder now severs the tympan-sheet at the perforated line.

Many changes may be made in the mechanical details by which this invention is carried into effect. It is to be understood, therefore, that the invention is to be considered as generic in its nature and is not to be limited to the specific forms of mechanism set forth in the foregoing specification. Certain parts of the construction are novel in themselves and are capable of independent use. It is to be understood, therefore, that such use is contemplated.

What I claim is—

1. The combination with a cylinder, of 120 means for supplying an offset-web thereto, and means for separating a sheet from said web, substantially as described.

2. The combination with a cylinder, of 125 means for intermittently supplying an offset- web thereto, and means for separating from said web a sufficient length to form an offset- sheet, substantially as described.

3. The combination with a cylinder, of 130 means for intermittently supplying a perfo- rated offset-web thereto, and means for sepa- rating from said web a sufficient length to

form an offset-sheet, substantially as described.

4. The combination with a cylinder, of means for supplying an offset-web thereto, 5 means for causing the cylinder to seize the end of the web, and means acting to clamp the web in opposition to the pull of the cylinder and thus cause an offset-sheet to be separated therefrom, substantially as described.

5. The combination with a cylinder, of means for intermittently supplying an offset-web thereto, means for causing the cylinder to seize the end of the web, and means acting 15 to clamp the web in opposition to the pull of the cylinder and thus cause an offset-sheet to be separated therefrom, substantially as described.

6. The combination with a cylinder, of 20 means for supplying an offset-web thereto, means for causing said cylinder to seize the web once in a predetermined number of revolutions, and a clamping device acting to hold the web against the pull of the cylinder where- 25 by an offset-sheet is separated therefrom, substantially as described.

7. The combination with a cylinder having grippers, of means for intermittently supplying an offset-web thereto, and an intermitt- 30 ently-operated clamping device acting to hold the web against the pull of the cylinder whereby an offset-sheet is separated therefrom, substantially as described.

8. The combination with a cylinder having 35 means for seizing the end of a web, of a table, means whereby an offset-web is fed over said table, and a clamping device acting to hold the web to the table after it has been seized by the cylinder and operating in connection with the web-seizing means on the 40 cylinder to separate an offset-sheet from the web, substantially as described.

9. The combination with a cylinder having 45 means for seizing the end of a web, of a movable table, means whereby an offset-web is fed over said table, and a clamping device acting to hold the web to the table after it has been seized by the cylinder and operating in connection with the web-seizing means 50 on the cylinder to separate an offset-sheet from the web, substantially as described.

10. The combination with a cylinder, of 55 means for supplying an offset-web thereto, means for releasing and removing from the cylinder an offset-sheet which has been used sufficiently, means for seizing the end of the offset-web, and means for separating an offset-sheet from the web, substantially as described.

60 11. The combination with a cylinder, of means for supplying an offset-web thereto, means for releasing and removing from the cylinder an offset-sheet which has been used sufficiently, means for seizing the end of the offset-web, means for separating an offset- 65 sheet from the web, and means for bringing

70 said releasing, seizing and separating mechanism into operation once in a predetermined number of revolutions of the cylinder, substantially as described.

12. The combination with a movable table, of a movable paper-guide located over one end of the table, and means for causing said guide to depress the end of the paper which extends beyond the table beneath the level 75 of the table, substantially as described.

13. The combination with a cylinder having grippers, of a movable paper-feeding table, means for depressing the end of the paper which extends beyond the table into 80 the path of the grippers on the cylinder, substantially as described.

14. The combination with a cylinder having grippers, of a movable paper-feeding table, a shaft supported over one end of the 85 table, means carried by the shaft for raising and lowering the table, and means also carried by the shaft for depressing the end of the paper which extends beyond the table into the path of the grippers on the cylinder, 90 substantially as described.

15. The combination with a cylinder having grippers, of a movable paper-feeding table, a shaft located on one end of the table, means carried by the shaft for raising and 95 lowering the table, a paper-guide also carried by the shaft and operating to depress the end of the paper which extends beyond the table into the path of the grippers on the cylinder, and a paper-clamping device, substan- 100 tially as described.

16. The combination with a cylinder having grippers, of a movable paper-feeding table, a shaft located on one end of the table, means carried by the shaft for raising and 105 lowering the table, a paper-guide also carried by the shaft and operating to depress the end of the paper which extends beyond the table into the path of the grippers on the cylinder, and a paper-clamping device carried by the shaft, substantially as described. 110

17. The combination of the regular printed-sheet grippers, offset-sheet grippers bearing on an incline of the edge of the cylinder-shell, and pins for lifting the edge of the offset- 115 sheet, substantially as described.

18. The combination with a cylinder, of a set of sheet-holding grippers, a second set of grippers, and lifting devices connected to and operated by the second set of grippers, sub- 120 stantially as described.

19. The combination with a cylinder, of a set of grippers, a set of sheet-lifting pins, levers by which the pins are operated, and a loose connection between said pin-operating 125 levers and the grippers, whereby movement of the grippers in each direction will operate the pins, substantially as described.

20. The combination with a cylinder, of a gripper-shaft, a set of grippers mounted thereon, lugs on the grippers, a set of sheet-lifting pins, levers by which the pins are operated, 130

and a pin extending from said levers and lying between the lugs on the grippers, substantially as described.

21. The combination with a cylinder, of devices for intermittently supplying an offset-web thereto, means for separating from said web a sufficient length to form an offset-sheet, and intermittently-operated means for removing from the cylinder the used offset-sheet, substantially as described.

22. The combination with a cylinder, of devices for supplying an offset-web thereto, means for separating from said web a sufficient length to form an offset-sheet, and means for delivering said offset-sheet together with the printed sheet, substantially as described.

23. The combination with a cylinder, of devices for intermittently supplying an offset-web thereto, means for separating from said web a sufficient length to form an offset-sheet, and means operating once in a predetermined number of revolutions of the cylinder to deliver the offset-sheet together with the printed sheet, substantially as described.

24. The combination with a cylinder hav-

ing grippers, of a movable cam for operating said grippers, mechanism for moving the cam, means for bringing said mechanism into operation once in a predetermined number of revolutions of the cylinder, means for feeding an offset-web to the grippers, and a clamping device operating in connection with the grippers to separate an offset-sheet from the web, substantially as described.

25. The combination with a cylinder having grippers, means for feeding an offset-web to the grippers, a clamping device operating on the web in opposition to the pull of the grippers, mechanism for operating the clamping device and a common locking device operating to simultaneously release the gripper-operating mechanism and the clamp-operating mechanism, substantially as described.

In testimony whereof I have hereunto set my hand in the presence of two subscribing witnesses.

THOMAS M. NORTH.
